UNITED STATES PATENT OFFICE.

EDWARD BAUM, OF PHILADELPHIA, PENNSYLVANIA.

EAR-DRUM PROTECTOR OR EAR-STOPPER.

1,344,935.

Specification of Letters Patent. Patented June 29, 1920.

Application filed September 19, 1918, Serial No. 254,740. Renewed November 24, 1919. Serial No. 340,240.

To all whom it may concern:

Be it known that I, EDWARD BAUM, a citizen of the United States, residing in the city and county of Philadelphia, State of Pennsylvania, have invented a new and useful Ear-Drum Protector or Ear-Stopper, of which the following is a specification.

It is well-known to specialists in otology and to laymen as well, that soldiers, sailors, gunners, operators of airplanes, riveters in 10 boiler shops and on the hulls of ships and elsewhere in the shipbuilding industry, and in similar occupations, frequently suffer from bursted, ruptured or damaged ear drums caused by air disturbances emanating from or following detonations caused by 15 ordnance or from the excessive air disturbances incident to the above occupations, or in the case of divers or bathers, from the 20 entrance of water into the auditory canal.

It is the common practice at the present time for gunners, artillerists and others desiring to protect the ears, to insert cotton in 25 their ears, which practice is injurious, since it oftentimes results in the fine filaments of the cotton getting into the wax and producing irritation, inflammation, abscesses of the ear or other disturbances to the ear or Eustachian tube, and to obviate the foregoing, the 30 object of my present invention is to provide a light, pneumatic, pliable and durable ear drum protector or ear stopper permanent and stable in character and adapted for repeated insertions in the auditory canal, and 35 which can be readily inserted into the meatus or external ear canal and readily withdrawn therefrom, whenever desired or necessary for the purpose of restricting, excluding and preventing the entrance of air, 40 sound or concusional waves or convections into the ear channel, thereby protecting the organs of the inner ear from excessive or injurious vibrations, and indirectly protecting the entire nervous system from shock, 45 such as "shell shock" by severe sound.

To the above ends, my novel ear drum protector or ear stopper consists of a hollow, hermetically sealed body, filled with air, whose exterior terminus, which is initially 50 inserted in the ear channel, is slightly thickened and convex to conform to the normal concavity of the human ear drum, the outer portion of my novel ear drum protector being closed by a diaphragm, flange or 55 closure having an exteriorly projecting knob or finger piece adapted to be grasped manu-

ally by the thumb and finger of the user for facilitating the insertion and withdrawal of the ear drum protector with respect to the meatus, said outer flange having projecting 60 inwardly therefrom, a pendulum-like sound absorbing member, having an enlarged terminus for the dual purpose of facilitating the insertion of the device into the ear canal, and for the further purpose of absorbing any excessive air vibrations which may impinge on the outer flange or closure.

My invention further consists in the novel provision of a series of longitudinally extending grooves or channels for the dual 65 purpose of ventilating and drainage, which extend longitudinally of the device and which have the additional function of preventing damage being done to the ear drum by the compression of air against the ear 70 drum during the insertion of the device, since any air contained within the ear canal between the ear drum and the forward portion of my ear drum protector has ready 75 egress through said external longitudinal 80 channels during the insertion of the device in position.

I further provide my novel ear drum protector with a thickened outer wall and a somewhat thinner inner wall or neck at 85 about the point where the outer flange or closure joins the body, which in conjunction with the longitudinal channels aforesaid permits the ear drum protector to readily and automatically slightly expand 90 and adjust itself to the meatus of the user, and by my provision of the outer knob, the device can be readily inserted and withdrawn from the meatus.

To the above ends, my invention consists 95 of a novel pneumatic ear stopper having a plurality of barriers to absorb the excessive air vibrations and prevent them from reaching or injuriously affecting the ear drum, the device being provided with means for 100 readily inserting and withdrawing it from the ear canal, the resultant construction being of one piece of material, containing an internal air cushion, so that there is no liability of damage to the ear canal or the ear 105 drum during the insertion or withdrawal of the device, which retains its position in the ear without accidental displacement or the slightest irritation.

For the purpose of illustrating my invention, I have shown in the accompanying drawings one form thereof which is at pres-

ent preferred by me, since the same will give in practice satisfactory and reliable results, although it is to be understood that the various instrumentalities of which my invention consists can be variously arranged and organized and that my invention is not limited to the precise arrangement and organization of these instrumentalities as herein shown and described.

10 Figure 1 represents a perspective view of an ear drum protector or ear stopper embodying my invention.

Fig. 2 represents a longitudinal, sectional view on line 2—2 of Fig. 1.

15 Fig. 3 represents an end view of Fig. 2.

Fig. 4 represents a sectional view of a human ear, showing the manner of using my device.

20 Similar numerals of reference indicate corresponding parts.

25 Referring to the drawings:—

1 designates my novel construction of ear drum protector or ear stopper, the same comprising a body portion 2 having its outer 30 end or terminal as 3 convex, so as to conform generally to the concavity of a normal human ear drum, it being noted that the portion 3 of the body is slightly thicker than the upper portion or neck 4, whereby 35 a slight resiliency is permitted at about this point to facilitate the insertion and withdrawal of the device and to enable one standard size of protector to conform to ear canals of different sizes.

40 35 designates an outer diaphragm, flange or closure, the mode of construction being such that it hermetically seals the internal air chamber 6 of the ear drum protector, said closure 5 having a knob or projection 7 serving as a handle attached thereto to facilitate the insertion and withdrawal of the device from the ear canal. It will be noted that the outer periphery of the closure 5 is slightly larger than the greatest diameter 45 of the body 2, so as to slightly limit the extent of inward movement of the protector, as will be understood from Fig. 4.

50 50 8 designates an internally projecting pendulum-like sound absorbing body or pendant having its end or terminal 9 slightly enlarged and terminating a short distance from the inner wall of the outer terminal 3, as will be understood from Fig. 2, the function of said parts 8 and 9 being of a 55 dual character, since they not only facilitate the ready insertion of the device into the ear canal, but also, in addition, after the ear drum protector is in position, enable any excessive sound vibrations to be absorbed 60 and arrested not only initially by the flange or outer barrier 5, but also by the pendulum-like central internal body 8, so that there are in reality three sound absorbing barriers in my novel device interposed before the human 65 ear drum when the device is in position, the

first barrier being the flange or closure 5, the second, the pillar or post 8, and the third the outer thickened terminal wall 3.

70 I desire to call particular attention also to the function of the longitudinally extending grooves or ventilating channels 10, which begin at a point under the bottom lip or flange 11 and merge into the body 2, as will be understood from Figs. 1 and 2, since said grooves permit the escape of any air 75 between the terminal 3 and the human ear drum within the meatus when the device is pushed inwardly into the position seen in Fig. 4, and, in addition, the channels 10 permit of the necessary ventilation and drainage 80 and also permit of the device to be slightly compressed during insertion, and after insertion permit a slight expansion, so that a single standard size ear drum protector of my invention will accommodate human ear canals of varying sizes.

85 The manner of using my novel ear drum protector or ear stopper will be apparent to those skilled in the art, it being only necessary to grasp the knob or handle 7 and 90 insert the device in the ear canal, as seen in Fig. 4, it being apparent therefrom that the internal pressure upon the handle 7 causes the diaphragm 5 to flex inwardly, pushing the sound absorbing post 8 inwardly until its terminal 9 contacts with the juxtaposed inner wall 3 of the thickened body 2. The portion 3 thereupon becomes slightly elongated assuming more of a conical contour, which facilitates its insertion 100 into the ear canal, and the slight momentary backward air pressure dilates the neck 4, near the junction of the body and diaphragm, thus slightly elongating the entire device and thus facilitating its insertion 105 as seen in Fig. 4. The device having been placed in position will, by reason of the internal air cushion and the provision of the channels 10, automatically expand slightly and snugly and painlessly assume the contour 110 of the contiguous wall of the meatus.

When it is desired to withdraw the ear stopper, this can readily be effected by a slight pull on the handle 7, which flexes the diaphragm 5 outwardly and slightly 115 elongates the body 2, thereby enabling the same to be readily withdrawn.

120 It will be apparent to those skilled in the art, that my novel device is pneumatic and resilient, and being provided with the ventilating and drainage grooves or channels 10, all of which permit a slight compression during insertion, no injury to the ear drum 12 or auditory canal 13 can occur, during the insertion and withdrawal of the device, 125 which is readily effected by the provision of the handle or knob 7.

130 The presence of the pneumatic hermetically sealed cavity 6 creates an even air cushion throughout the exterior contour of

the device, and after the latter has been seated in position, as seen in Fig. 4, the internal pneumatic pressure obviously expends its force upon the most resilient or thinnest portion of the device, as at the neck 4, and causes the device to accommodate itself to any irregularities of the ear canal, and to be effectively locked therein.

It will be further apparent that the outer diaphragm 5 will effectively prevent the entrance of air, sound waves or detonations, and the central, internal, pendulum-like pillar or post 8 will further absorb the sound waves, which two barriers in conjunction with the thickened terminal 3 will effectively prevent shell shock and injury to the ear drum or inner ear. The longitudinal grooves or channels 10 on their interior assume the appearance of corrugations, whose constriction is limited by the presence of the internal sound absorbing pendant 8.

In the manufacture of my device, I preferably employ a high grade of rubber or similar resilient material, which may have a very small proportion of sulfur or whiting commingled therewith, whereby the device will possess the requisite toughness and durability, and, in addition, will not injure the meatus or ear canal during its insertion and withdrawal therefrom.

It will, however, be evident that other ingredients may be employed without departing from the spirit of my invention and I do not desire to be limited to any particular composition of matter in the manufacture of my novel device.

I am the first in the art to produce an ear drum protector having the three sound absorbing barriers, as the diaphragm 5, the pendant 8, and the thickened wall 3, either alone or in conjunction with the grooves 10, and my claims to these features are to be interpreted with the scope accorded to inventions of this character.

It will now be apparent that I have devised a novel and useful construction of an ear drum protector or ear stopper, which embodies the features of advantage enumerated as desirable in the statement of the invention and the above description, and while I have, in the present instance, shown and described a preferred embodiment thereof which will give in practice satisfactory and reliable results, it is to be understood that the same is susceptible of modification in various particulars without departing from the spirit or scope of the invention or sacrificing any of its advantages.

Having thus described my invention, what I claim as new and desire to secure by Letters Patent, is:—

1. An ear drum protector, consisting of a hollow body having a chamber filled with air, said body having at one end thereof a rounded outer terminal, a diaphragm se-

cured to the opposite end thereof and forming a closure for said air chamber, and an internal pendant sound absorbing member secured to said diaphragm and projecting into said air chamber.

70

2. An ear drum protector, consisting of a hollow body filled with air, said body having at one end thereof a rounded outer terminal, a diaphragm secured to the opposite end thereof, and having an exteriorly projecting knob thereon, and an internal pendant sound absorbing member also projecting from said diaphragm and contained in the air chamber.

75

3. An ear drum protector, consisting of a hollow body filled with air, said body having at one end thereof a convex outer terminal, a diaphragm secured to the opposite end thereof, and an internal pendant sound absorbing member contained in the air chamber, said body having a reduced neck at the point of its attachment to said diaphragm.

80

4. An ear drum protector, consisting of a hollow body filled with air, said body having at one end thereof a convex outer terminal, a diaphragm secured to the opposite end thereof, and an internal pendant sound absorbing member, said body having a reduced neck at the point of its attachment to said diaphragm, and the external periphery of said body at said neck being provided with longitudinally extending ventilation and drainage grooves.

95

5. A pneumatic ear drum protector, consisting of a hollow body filled with air, said body having a thickened external convex wall, a diaphragm secured to the opposite portion thereof, and an internal pendant sound absorbing member, whereby three sound arresting and absorbing barriers are produced.

100

6. A pneumatic ear drum protector, consisting of a hollow body filled with air, said body having a thickened external convex wall, a diaphragm secured to the opposite portion of said body provided with a handle extending exteriorly therefrom, and an internal pendant sound absorbing member located in the air chamber and projecting from said diaphragm, whereby three sound arresting and absorbing barriers are produced.

110

7. A pneumatic ear drum protector, consisting of a hollow body filled with air, said body having a thickened external convex wall, a diaphragm secured to the opposite portion thereof, so as to hermetically seal the air chamber, and an internal pendant sound absorbing member having an enlarged end depending from said diaphragm and terminating a short distance from the juxtaposed inner wall of said convex wall, whereby three sound absorbing barriers are produced, said body being of reduced thickness at the point of its attachment to said

120

125

130

- diaphragm and provided with longitudinally extending ventilation and drainage grooves, said diaphragm being of greater diameter than the greatest diameter of said body.
8. An ear drum protector, consisting of a hollow body filled with air, said body having a thickened external convex wall, a diaphragm secured to the opposite portion thereof, so as to hermetically seal the air chamber, and an internal pendant sound absorbing member depending from said diaphragm and terminating a short distance from the juxtaposed inner wall of said convex end, whereby three sound arresting barriers are produced.
9. An ear drum protector, consisting of a resilient hollow body inclosing an air cham-

ber, one wall of said body having a handle projecting therefrom, and an internal pendant sound absorbing member projecting from said wall into said air chamber in substantial alinement with said handle.

10. An ear drum protector, consisting of a resilient hollow body inclosing an air chamber, one wall of said body having a handle projecting therefrom, and an internal sound absorbing member projecting from said wall into said air chamber in substantial alinement with said handle, said body having longitudinally extending external ventilation and drainage grooves therein.

EDWARD BAUM.
